UNITED STATES PATENT OFFICE.

THOMAS S. COLEMAN, OF BRANDENBURG, KENTUCKY.

WINDLASS WATER-ELEVATOR.

SPECIFICATION forming part of Letters Patent No. 639,149, dated December 12, 1899.

Application filed June 29, 1899. Serial No. 722,249. (No model.)

To all whom it may concern.

Be it known that I, THOMAS S. COLEMAN, a citizen of the United States, residing at Brandenburg, in the county of Mead and State 5 of Kentucky, have invented new and useful Improvements in Windlass Water-Elevators, of which the following is a specification.

My invention relates to an improved windlass water-elevator.

10 It is an object of the invention to provide improved means for automatically dumping the bucket during the lifting operation.

It is a further object of the invention to provide the well-casing with a pivoted spout, 15 which shall also operate as a closure for the casing, and to combine therewith mechanism for turning said spout upon its pivot in the lifting operation, whereby the bucket shall be caused to discharge its contents into the 20 spout, and for automatically turning said spout to a closed position and locking the same in such position as the bucket is lowered.

Further objects of the invention relate to 25 the construction and combination of parts, all as hereinafter more fully described, and specifically pointed out in the claims.

I have illustrated my invention in the accompanying drawings, in which—

30 Figure 1 is a sectional side elevation with the bucket and spout in their lowered position. Fig. 2 is a similar section showing the bucket and spout in a raised position. Fig. 3 is a front elevation of the well-casing. Fig. 35 4 is a horizontal section on line 4-4 of Fig. 3, and Fig. 5 is a detail view of the spout and the arms for locking and raising the same.

Referring to the drawings, the reference-numeral 1 indicates the well-casing, having 40 an opening 2 in one side, across which opening extends a rod 3, which is secured at opposite ends to the casing.

The numeral 4 indicates the spout, which is pivoted by means of apertured lugs 5 on 45 the rod 3. The lugs 5 project from opposite sides of the bottom of the spout and are located nearer the upper or discharge end of the spout than they are to the opposite end. The spout 4 is of a size to snugly close the 50 opening 2 and tends normally to assume a perpendicular position by reason of the fact

that its point of pivotal connection is nearer one end than the other. Secured in the spout 4 and extending across the same and through the sides of the spout is a rod 7, 55 which is also located above the longitudinal center of said spout.

The numerals 8 9 indicate two arms, each of which is provided at one end with an extension 10, which is pivotally mounted at its 60 end on a projecting end of the rod 7 and secured thereon, as by means of flanged nuts 11, screwed on the projecting ends of said rod 7. The arms 8 and 9 are parallel with the sides 6 of the spout and extend from one 65 side to the other of the casing. The projections 10 make acute angles with the arms 8 9, as shown at 12, and these angular projections 12 are adapted to rest against the front of the casing, and thereby serve as stops to 70 prevent the arms 8 and 9 from passing beyond a horizontal position. In this position the spout 4 will occupy a vertical position, closing the opening 2, and as the free ends of the 75 arms 8 and 9 are in close proximity to the rear side of the casing it is evident that the spout 4 cannot be turned to afford access to the interior of the well or cistern until the arms 8 and 9 are lifted from a horizontal position. This can only be effected by raising the 80 bucket, as will presently appear. In each arm 8 9 is provided a longitudinal slot 13, which slots extend nearly to the outer or free ends of said arms. Extending between the arms 8 and 9 and slidably mounted at opposite ends in the slots 13 is a cross-bar 14, having 85 a central aperture 15, through which passes the rope 16, secured at its lower end in the top of a bucket 17. Said bucket is provided in its bottom with an upwardly-opening 90 valve 18, which normally closes an opening in said bottom, and is provided with a stem 19, which projects below the bottom of the bucket.

The numeral 20 indicates a cage or guard 95 for the valve 18.

At a suitable distance above the top of the bucket the rope 16 is provided with a knot or stop 21, which is designed to engage the under side of the cross-bar 14 as the rope is 100 raised. Said rope passes over a grooved wheel 22 at the top of the casing and thence over a

winding-drum 23, to which it is secured. Said winding-drum is operated by a crank 24 and has a ratchet-wheel 25, controlled by a pawl 26.

The operation is as follows: As the drum 23 is revolved the rope 16 is wound thereon, passing upward through the aperture 15, and the stop 21 comes in contact with the under side of cross-bar 14. The arms 8 and 9 will now be raised, the cross-bar sliding outward in the slots 13. This continues until the cross-bar reaches the ends of the slots, when the pull of the rope will operate to turn the spout 4 on its pivot 3. Owing to the pivotal connection shown and described the spout 4 will be moved toward a horizontal position with greater rapidity than the bucket rises, and the arrangement is such that when the rear end of the spout has passed beyond the horizontal it will strike the stem 19, thereby raising valve 18 and allowing the water to discharge into the spout. It will be seen that the operations described are all performed by the mere act of winding the rope 16 upon the drum. When the rope is unwound, the parts 25 automatically resume their normal positions by gravity. In this position the arms 8 and 9 securely hold the spout from turning, as previously described, and thus prevent the possibility of anything being thrown in the well. 30 By snugly closing the opening in the casing I also prevent dust, leaves, insects, and the like from getting into the well.

Having thus fully described my invention, what I claim as new is—

35 1. In a windlass water-elevator, the combination with the casing, of a spout pivotally mounted thereon in a normally-vertical position and its pivot being above the center, arms pivotally secured to said spout on either side 40 thereof and below the said pivot, each of said arms having a longitudinal slot, a cross-bar slidably mounted in said slots and having a central aperture, a rope passing through said

aperture and beneath said cross-bar having a stop, a bucket secured on the lower end of said 45 rope having an opening in its bottom, means for winding said rope, and a valve normally closing said opening and having a stem projecting through the same, whereby, when the bucket is raised to the top of the well, the 50 spout will be turned to engage said stem and cause the contents of the bucket to be discharged into the spout, substantially as described.

2. In a windlass water-elevator, the combination with the casing having an opening, of a spout pivotally mounted thereon in a normally-vertical position and when in such position adapted to close said opening, horizontal arms having upright extensions pivotally 60 secured, respectively, on opposite sides of said spout, said arms extending from side to side of the casing and resting against the front thereof at the point of connection with such extensions, for the purpose of locking the spout, 65 as described, and each of said arms having a longitudinal slot, a cross-bar slidably mounted in said slots and having a central aperture, a rope passing through said aperture and beneath said cross-bar having a stop, a bucket 70 secured on the lower end of said rope having an opening in its bottom, means for winding said rope, and a valve normally closing said opening and having a stem projecting through the same, whereby, when the bucket is raised to the top of the well, the spout will be turned to engage said stem and cause the contents of the bucket to be discharged into the spout, 75 substantially as described.

In testimony whereof I have hereunto set 80 my hand in presence of two subscribing witnesses.

THOMAS S. COLEMAN.
